(57) **CLAIM**

The ornamental design for an otoscope, as shown and described.

DESCRIPTION

FIG. 1 is a left side elevational view of an otoscope according to the present invention.

FIG. 2 is a right side elevational view of the otoscope of FIG. 1.

FIG. 3 is a front elevational view of the otoscope of FIG. 1.

FIG. 4 is a rear elevational view of the otoscope of FIG. 1.

FIG. 5 is a top plan view of the otoscope of FIG. 1.

FIG. 6 is a bottom plan view of the otoscope of FIG. 1; and,

FIG. 7 is a perspective view of the otoscope of FIG. 1.

The dashed lines illustrate environment that does not form a

part of the present invention, and no claim is made to the

material illustrated with dashed lines.
